UNITED STATES PATENT OFFICE

2,672,129

CHIPPING HAMMER

Howard R. Fischer, Detroit, Mich., assignor to
 Chicago Pneumatic Tool Company, New York,
 N. Y., a corporation of New Jersey

Application March 17, 1949, Serial No. 81,935

4 Claims. (Cl. 121—10)

1

This invention relates to a chipping hammer. It is an object of the present invention to provide a chipping hammer which is equipped with a high velocity jet blowing device for cleaning the work surfaces which have been worked upon with the hammer that will direct a steady high velocity stream of air from the hammer nose and will remove an accumulation of cuttings that are not removed by the exhaust air of the hammer and wherein the action of the hammer and of the blower is effected with a common control lever which is squeezed or pushed with the thumb to effect hammer action and which with the same thumb may be lifted to start blower action and without having to move the hammer to direct the jet of air onto the work surface.

It is another object of the invention to provide a chipping hammer which has a sensitive throttle control whereby the hammer may be easily regulated to deliver either light, delicate taps, or heavy, hammer-like blows and whereby to render the hammer adapted for use for many different purposes.

It is another object of the invention to provide an automatic distributing valve arrangement for delivering air under pressure alternately to opposite sides of the hammering piston comprising separable valve case sections and a valve element having two thin flanges spaced apart and an integral stem guided by the valve case sections and wherein the flanges need not have air tight connection with the walls of the case sections, but between their peripheries and the walls provide the passages through which the air is diverted to the opposite sides of the valve to effect the movement of the valve from one position to the other and to pass the air to the opposite sides of the hammering piston, whereby to provide a valve arrangement for chipping hammers which will have little wear and long life.

It is another object of the invention to provide a simple chisel retaining device for chipping hammers which permits the easy removal of the chisel and makes the changing of chisels a simple, easy operation, and whereby when the chisels are in place they are positively retained against outward movement from the hammer casing.

It is another object of the invention to provide a chipping hammer comprising a cylinder sleeve, hammering piston and distributing valve parts which can be loosely assembled in order in the outer casing and which will be held in place by the single connection of a throttle and blower valve containing cylinder head to the outer casing.

Other objects of the invention are to provide

2

a chipping hammer having a jet blowing device, a distributing valve arrangement and a positive retaining device for the chisel, which is of simple construction, has a minimum number of parts, easy to assemble, inexpensive to manufacture, easy to operate, compact, easily held in the two hands and manipulated, and efficient in operation.

For other objects and for a better understanding of the invention, reference may be had to the following detailed description taken in connection with the accompanying drawing, in which

Fig. 1 is a perspective view of the chipping hammer embodying the features of the present invention being used on a wall to chip the mortar from between bricks thereof and with the operating lever depressed for chiseling action.

Fig. 2 is a perspective view of the chipping hammer being used on the wall and with the operating lever elevated with the thumb to project the high velocity jet of air upon the work surface to clean the same.

Fig. 2a is a perspective view of the chipping hammer being used to remove weld flux.

Fig. 3 is a fragmentary side elevational view of the chipping hammer with a portion thereof broken away and shown in section through the region of the air jet blower valve and with the operating lever elevated to depress the same for blower action.

Fig. 4 is a longitudinal sectional view of the chipping hammer with the hammering piston projected toward the nose end of the hammer and as viewed on line 4—4 of Fig. 2.

Fig. 5 is a longitudinal sectional view taken on line 5—5 of Fig. 4.

Fig. 6 is a perspective view of the cylinder sleeve removed from the main casing.

Fig. 7 is a longitudinal sectional view of the chipping hammer with the operating lever depressed for hammering action and as viewed on line 7—7 of Fig. 1.

Figs. 8 and 9 are respectively enlarged transverse sectional views taken on lines 8—8 and 9—9 of Fig. 7.

Fig. 10 is a collective view of the distributing valve casing sections which are in section and of the valve element which is shown in side elevation.

Fig. 11 is an enlarged fragmentary and sectional view of the hammer taken through the distributing valve arrangement with the hammering piston in its rearward position within the cylinder sleeve and the valve element of the valve arrangement being positioned to extend air to the

forward part of the cylinder chamber.

Fig. 12 is a fragmentary sectional view similar to Fig. 11, but with the hammering piston extended forwardly in the cylinder to engage with the end of the chisel and with the valve element positioned to extend air to the rear part of the cylinder sleeve.

Fig. 13 is a perspective view of the hammer looking upon the chisel retaining device in the nose end of the hammer for the securement of the chisel.

Fig. 14 is a fragmentary sectional view of the nose end of the hammer taken on line 14—14 of Fig. 13.

Fig. 15 is a transverse sectional view taken on line 15—15 of Fig. 14.

Fig. 16 is a transverse sectional view similar to Fig. 15, but with the retaining plug having been turned to expand the retaining spring and to free the plug of the chisel element for the release of the same.

Fig. 17 is a longitudinal sectional view taken on line 17—17 of Fig. 16.

Referring now to the figures, the chipping hammer of the present invention comprises generally an outer casing 21 having an integral nose end portion 22 adapted to receive a chisel 23 within its opening 24. This chisel 23 is held within the opening 24 by a quick release key plug 25. The outer casing 21 is internally threaded at 26 to receive a threaded portion 27 of a cylinder head 28 having a throttle valve element 29 adapted to be depressed by a manually-operable lever 31 pivotally connected to the cylinder head 28 at 32. This same lever 31 when pivoted away from the throttle valve element 29 is used to depress a blower valve element 33 to cause air to be directed through the cylinder head and casing and holes 34 in the nose end portion 22 of the outer casing 21 to direct air upon the work surface. This air passes to the work surface with great force and removes such particles and chips from the surface which have not been removed by the exhaust air blast and in the manner as illustrated in Fig. 2.

Fitted within the outer casing 21 is a cylinder sleeve 35 having a hammer piston 36 slidable therein. This hammer piston 36 has a projection 37 adapted to tap the end of the chisel 23 which has been extended into the nose end portion 22 of the outer casing 21. Fixed within the outer casing 21 by the cylinder head 28 is a distributing valve arrangement 38 with a double flange valve element 39 and adapted to cause the passage of air to first one end of the cylinder sleeve 35 and then to the opposite end thereof whereby to cause the reciprocation of the hammer piston 36 at a speed dependent upon the extent of downward movement of the lever 31 and of the throttle valve element 29. The hammer piston 36 can accordingly be made to deliver either fast blows upon the chisel 23 or slow taps.

The cylinder head 28 is locked in the outer casing 21, against turning movement by a locking ring 41 seated in aligned recesses 42 and 43 of the respective casing and head parts, and having a radially inwardly bent end 44 within aligned peripheral slots 45 and 46 of the respective casing and head parts. An air hose 49 is connected to a threaded opening 48 in the cylinder head 28. Extending from this threaded opening 48 is a valve chamber 51 into which valve elements 29 and 33 are extended to open ports 52 and 53 respectively. A plug 54 is disposed in a threaded opening at the bottom of the cylinder head where-

by, if desired, an attachment of the hose 48 can be made to the bottom of the cylinder head. The plug 54 can be then inserted in the threaded opening 49.

Air passes from the valve chamber 51 through port 52 when lever 31 is depressed and the valve element 29 lowered into the chamber 51 so that its closing portion 55 drops sufficiently to allow air to pass to a groove 56 on the valve element 29 and to distributing valve chamber 57 in the cylinder head. The valve element 29 is urged toward its elevated and closed position by a spring 58 and plug 59.

The distributing valve arrangement 38 comprises two opposing valve seat parts or casing sections 61 and 62 separable from one another upon the distributing valve arrangement being made free of the casing but held closed upon one another by the cylinder head 28 on being connected with the outer casing 21, Figs. 4, 11 and 12. Circumferentially spaced within the casing section 61 are a plurality of longitudinally-extending holes 63 through which the live air is passed from the valve chamber 57 to a manifold recess 64 cut in the face of the casing section 61. From the manifold recess, the live air passes radially inwardly through a thin slot 65 provided between the casing sections 61 and 62 and into space 66 provided between flanges 67 and 68 of valve element 39. This space 66 provides a miniature reservoir for the air and permits the valve element 39 to shift from one position to the other. On the valve casing section 61 is a seat 69 against which the valve element is forced when moved into casing section 61. On the casing section 62 is a valve seat 70 against which the valve element 39 is forced when the valve element is moved toward that section. The valve element 39 has a stem 71 which enters a hole 72 to be supported and guided in its axial movement within the distributing valve casing sections.

The two flanges 67 and 68 of the valve element 39 are slightly smaller in diameter than the bores of the valve casing sections which allow the correct volume of air to flow past the flanges to the front and rear of the cylinder sleeve 35 to operate the hammering piston 36. If the valve element 39 has been moved to the right, as viewed in Figs. 5, 7 and 11, air passes flange 67, seat 69, longitudinally-extending chamber 75 in the valve section 61, radially-extending passage 76, aligned peripheral slots 78 and 79 in the respective valve casing sections 61 and 62, longitudinally-extending slot 81 in the cylinder sleeve 35, holes 82 in the cylinder sleeve to the front of cylinder sleeve chamber 83 and ahead of the piston 36 whereby to return the piston 36 to the rear of the cylinder sleeve chamber. While this is taking place, the air in the rear of the chamber 83 is exhausted through large hole 84 to a longitudinally-extending passage 85, Fig. 5, provided by relief 86 cut from the exterior of the cylinder sleeve 35. This relief begins at a point on the cylinder sleeve removed from the rear end thereof and terminates at the forward end of the cylinder sleeve to allow the air to pass forwardly thereof to air holes 34 and exhausted upon the working surface. This air will not have the steady and high pressure blowing effect of the air which is delivered directly when the blowing valve 33 is depressed, but will keep the work surface cleared of the less difficult cuttings to remove. The manner in which the blowing air arrives or is passed through the parts will be set forth later herein.

The cylinder sleeve 35 has an end opening 87

through which the hammering portion 37 of the piston 36 is projected. The portion 37 is guided into the opening 87 by a flaring 88. The nose end of the cylinder 35 is peripherally relieved at 89 to provide an annular passage 91 through which the air leaving longitudinal passage 85 passes to air holes 34. The cylinder sleeve 35 has a small bleed port 92 for relieving any pressure back of the piston during the blowing process, otherwise the piston 36 would have a tendency to flutter or make a short stroke.

Forwardly of the hole 84 in the cylinder sleeve 35 is an exhaust hole 93 which is uncovered by the piston as it moves rearwardly in the chamber 83. The pressure in the front end of the chamber 83 thereupon instantly drops. The hammer piston 36 continues to move rearwardly under its momentum and compresses the air in the rear end of the chamber 83 to shift the valve element 39 rearwardly to engage seat 69. The pressure will thereupon drop in the passages leading from the distributing valve 38. The variable force of the blow results from the light sensitive pulley valve element 39, the throttle valve 55 and the control lever 31.

The air from the small chamber 66 between the flanges 67 and 68 of the valve element 39 then passes the flange 68, seat 70 and port 94 in the casing section 62, to enter the rear of the chamber 83 to urge the piston forward for its next hammering action. As soon as the exhaust port 84 is uncovered on the forward stroke, the pressure on the piston diminishes and pressure is built up between the casing sections to move the valve element forward to engage seat 70 and to open the passages to the forward end of the chamber 83 and effect the return of the piston.

While only one relief 86 and one groove 81 has been described, it is to be understood that the cylinder sleeve 35 also has a diametrically opposite relief 86 and a diametrically opposite groove 81. The valve casing sections 61 and 62 likewise have corresponding passages and slots for the delivery of air to the diametrically opposite groove 81. Likewise, the relief 86 at the opposite side of the sleeve has exhaust openings 84, 92 and 93 and terminates at the annular relief 89 on the nose end of the cylinder sleeve.

Upon release of the operating lever 31, the throttle valve 29 is returned to its closed position and the lever 31 is raised to its neutral position, as viewed in Fig. 4. By lifting the lever rearwardly, the blower valve 33 is depressed and air will be admitted from the chamber 51 to the blowing air port 53. This blower valve 33 is normally urged toward a closed position by a spring 95 and a plug 96 threaded into the cylinder head 28. There are two ports 53, Fig. 5, connecting respectively with longitudinally-extending passages 97 in the cylinder head 28 which flare outwardly to provide outlet ports 98 on the forward end of the cylinder head.

The cylinder head 28 is provided with an annular recess 99 whereby to provide an annular chamber 101 between the cylinder head and the casing 21. This annular chamber 101 has communication with slots 78 and 79, Fig. 11, in the respective valve casing sections 61 and 62 and to the grooves 81 on the exterior of the cylinder sleeve 35. From these grooves, the air enters the front of the chamber 83, causing the hammering piston 36 to be moved rearwardly and to uncover the sleeve opening 93 to permit the air to pass through passages 85, annular space 75

91 and holes 34. This air moves in a steady stream and will be projected with great force upon the working surface to clear away any accumulation of cuttings for which the exhaust air is not sufficient. It will accordingly be seen, that by simply reversing the movement of the manually-operable lever 31 from its position depressing the throttle valve 29 for chipping action to a position to depress the blower valve 33, blower action will be effected and a removal of the cuttings or chips on the surface being worked will result.

Referring now particularly to Figs. 13 to 17, there is shown the chisel retaining arrangement. The chisel 23 is generally of square section relieved at its corners, at the portion thereof adapted to fit the opening 24. This portion of the chisel is indicated at 103 and intermediate the length of this portion is a slot 104 adapted to receive the retaining plug 25. This retaining plug is round and has a tapered projection 105 adapted to enter the chisel slot 104 and a shoulder 106 adapted to engage with a shoulder 107 of plug opening 108 in the nose end 22 of the casing 21. The retaining plug 25 is held in place with the projection 105 in the slot 104 of the chisel element by a split spring ring 109 adapted to fill an annular recess 110 on the exterior of the nose portion 22. The ends of the ring terminate against a handle portion 111 of the retainer element. On the retainer element below the handle portion is a cam surface 112 adapted to act upon the ends of the spring ring 109 to expand them and to cause the retainer element to be lifted within the opening 108 and to thereby release the chisel element from its opening 24. The retaining plug 25 is merely turned ninety degrees in order to release the chisel element. Upon the retaining plug being released from spring 109, it will be returned to its lowered position in the chisel slot under the action of the ends of the spring upon the cam surface 112 of the retainer element. The slot 104 in the chisel element is sufficiently long to permit the axial displacement of the chisel resulting from the hammering action.

The sleeve 35 with the piston 36, the distributing valve sections 61 and 62 with the valve element 39 disposed between them, are easily assembled within the outer casing 21 in the order mentioned and by the mere connection of the cylinder head 28 containing the valves 29 and 33 and the manually-operable lever 31 for operating these valve elements are secured firmly within the casing 21 against axial displacement. The ring 41 is finally snapped into place on the outer casing and the cylinder head to prevent the outward turning of the cylinder head from the outer casing 21.

The chipping hammer is of light weight, easily handled and has many uses. Some of such uses are channeling brick before repainting, cutting windings in electric motors, scraping barnacles from ship bottoms, cleaning putty from steel window sashes, chiseling wood in pattern shops, making grafting incisions in trees, removing heat treat scale, redressing millstones and numerous other uses.

While various changes may be made in the detail construction, it shall be understood that such changes shall be within the spirit and scope of the present invention as defined by the appended claims.

In a divisional application, Serial No. 367,215, filed July 10, 1953, are claims to the automatic

distributing valve arrangement and the chisel retaining device, both of which are disclosed herein and illustrated in the accompanying drawing.

What is claimed is:

1. An air operated chipping hammer comprising a casing having at one end a nose portion including a tool receiving opening and air holes for direction of air from said nose portion to a surface being worked upon with the hammer, a cylinder head removably affixed to the other end of the casing and having air inlet means, a hammer piston arranged for reciprocable movement within the casing, means including passageways for conducting exhaust air from the hammer piston portion to the air holes, a throttle valve arranged in the cylinder head for admission of live air for actuation of the hammer piston, a blower valve arranged in the cylinder head for admission of live air to the passageways leading to the air holes, and a unitary control means adapted for operation of either the throttle valve or the blower valve.

2. An air operated chipping hammer according to claim 1, wherein the unitary control means comprises a lever which is pivotally arranged so that in one direction of movement it operatively engages the throttle valve, and in the opposite direction of movement it operatively engages the blower valve.

3. An air operated chipping hammer according to claim 2, wherein the length of the lever about the pivot in the direction of the throttle valve is greater than the length of the lever about the pivot in the direction of the blower valve.

4. An air operated chipping hammer according to claim 3, wherein resilient means are arranged to urge both the throttle valve and blower valve toward closed position.

HOWARD R. FISCHER.
